Frank Schaefer
Attorney.

UNITED STATES PATENT OFFICE.

ERWIN CASSCA, OF GLOVERSVILLE, NEW YORK.

SOUND-MODIFYING MEANS.

1,342,662.

Specification of Letters Patent.

Patented June 8, 1920.

Application filed February 3, 1919. Serial No. 274,774.

To all whom it may concern:

Be it known that I, ERWIN CASSCA, a subject of the Emperor of Austria, residing in the city of Gloversville, in the county of Fulton and State of New York, have invented 5 new and useful Improvements in Sound-Modifying Means, of which the following is a specification.

This invention relates generally to sound 10 boxes for phonographs or the like, and particularly to sound modifying means for receiving the diaphragm vibrations at the point of maximum amplitude, the minor vibration being absorbed or deadened, to thereby 15 avoid the interference which would otherwise impair the pure reproduction.

The invention in the preferred form is illustrated in the accompanying drawings, in which:

20 Figure 1, is a section in elevation showing my improved sound modifier. Fig. 2, is a cross section taken on line 2—2 of Fig. 1.

A complete description of the sound box herein shown will be found in my copending 25 application for improvements in sound boxes for phonographs, or the like, filed June 11, 1917, Serial #173925, therefore I shall here limit myself to the description of the particular sound modifying means forming 30 the subject matter of this application.

To avoid variations in the vibrations of the diaphragm in the reproduction, I provide what I term a sound modifier, in the use of which the vibrations of the diaphragm 35 beyond the point of maximum amplitude thereof are deflected or damped, with the effect to render the sound waves delivered to the horn more sharp and clear.

To provide for this sound modifier the 40 upper portion of the wall of the sound opening is recessed at 10 to receive a sleeve extension 11, the upper edge of which is vertically slotted at diametrically opposite points, as at 12. The sound modifier comprises 45 a series of connected sections 13, of substantially similar structure but varying in diameter. Each section comprises an annular wall 14 having its minimum diameter at a point approximately half the height

thereof, the wall flaring above and below 50 said minimum line. The upper edge of the annular wall forming the section is projected downwardly, and formed in a return band, terminating in spaced relation to the wall, and forming with said wall, an approximately closed annular chamber 15 opening only from beneath. As previously 55 stated, the respective sections, of which four are here shown, are of successively increased diameter from the lower to the upper portion of the modifier, and each of the said sections above the lower sections have, at diametrically opposite points, depending strips 16 by means of which the particular section is secured to the next lowermost 60 section. There is thus provided an annular series of slot like openings 17 between the lower edge of each section and the rounded wall of the next lowermost section, providing 65 for the sound entrance into the modifier at a series of distinct but uniformly arranged points. The uppermost section is provided with projecting pins or strips 18 adapted to seat in the slots 12 of the sleeve 11, whereby the modifier is removably supported within the sleeve in a position directly and centrally above the diaphragm. 70

The sound box is provided with the usual casing 19 secured to the base with the sleeve, the casing rising above the sleeve and having 80 an extension 20 to which the horn or other sound conveyer 21 may be removably secured.

I claim:—

A sound box having a diaphragm and a 85 tone modifier removably carried by said box above the diaphragm, said modifier comprising a series of superposed sections of increasing diameter from the diaphragm, each section being connected to the one below at 90 determinate points to provide slotted openings between the sections, each section having an annular peripheral chamber, said chamber being open from beneath.

In witness whereof I have hereunto subscribed my name this 3d day of June, 1918. 95

ERWIN CASSCA.
